UNITED STATES PATENT OFFICE.

HENRY B. SAUERMAN, OF CHICAGO, ILLINOIS.

MATERIAL-MOVING APPARATUS.

1,159,106.

Specification of Letters Patent.

Patented Nov. 2, 1915.

Application filed February 9, 1914. Serial No. 817,640.

To all whom it may concern:

Be it known that I, HENRY B. SAUERMAN, a citizen of the United States, residing at Chicago, in the county of Cook and State of Illinois, have invented a new and useful Improvement in Material-Moving Apparatus, of which the following is a specification.

My invention relates to improvements in material-moving apparatus comprising, generally stated, an inclined cable-way supporting a traveling carriage thereon with a dumping-scraper or bucket connected with the carriage, and a hauling-line through the medium of which the movements of the carriage and bucket are controlled; and my objects are to provide an improved form of apparatus of this general character which will be highly efficient in operation, be readily and positively operated, and whereby accidental dumping of the contents of the bucket shall be avoided.

Referring to the accompanying drawings Figure 1 is a view in elevation of an apparatus constructed in accordance with my invention, the apparatus being shown in the position it assumes when dredging. Fig. 2 is a similar view of a part of the main and hauling cables and the carriage and bucket of Fig. 1, this view showing the main-cable taut and the bucket in the position it assumes while being moved up on the main-cable through the middle of the hauling-cable, the carriage and bucket being shown in a position closely adjacent to the point of dumping. Fig. 3 is a view like Fig. 2 showing the bucket in the act of dumping; and Fig. 4, an enlarged section taken at the line 4 on Fig. 2, and viewed in the direction of the arrow.

The inclined main-cable which would be supported, in practice, to extend across the ground to be excavated or dredged, is represented at 5 and is anchored at its lower end, as indicated at 6, and at its opposite, upper, end connects with a tauting mechanism of any suitable and well known construction secured to the upper end of a mast 7, and, as shown, formed of a system of pulleys 8 connected with a cable 9 which passes over a suitably operated drum 10, whereby the cable 9 may be slackened or made taut at will.

Mounted on the cable 5 to travel thereon is a carriage 11 which, in the construction illustrated, is formed of a pair of plates 12 and 13 spaced apart and connected with

bolts 14. Located between the plates 12 and 13 are pulleys 15 and 16 journaled on bolts 17, by which pulleys the carriage is supported on the cable-way 5 and is movable thereon.

The dumping-scraper or bucket, represented at 18, and which is supported from the carriage 11, is of a form generally used, its forward, open, digging-end being provided with a cutting-edge portion 19. The bucket 18 is provided at opposite sides near its closed, rear, end with lugs 20, one only of which is shown, with which the lower ends of a yoke 21 are pivoted, as indicated at 22, the upper end of the yoke 21 being pivotally connected with the carriage 11, as indicated at 23. The bucket 18 is thus pivotally hung from the carriage 11 and at a point in the rear of the center of gravity 75 of the bucket when loaded. The bucket 18 is connected at its front end, as indicated at 18^a, with one of the branches 24 and 25 of the draft-cable which unite, as shown in Fig. 2, a slight distance beyond the bucket 18, to 80 form a single draft-cable as is often the practice in constructions of this kind, the draft-cable shown being formed with a section 26, in the form of a head. The branch 25 of the draft-cable is preferably a chain 85 which extends over a coil-chain sprocket wheel 27 journaled between the plates 12 and 13 of the carriage 11 on a bolt 28, and connects at one end with a bail 29 on the forward end of the bucket 17 in advance of the 90 center of gravity of the latter. Rigid with the sprocket wheel 27 at opposite sides thereof, and located between the plates 12 and 13 and reinforcing plates 30 secured to the carriage and spaced therefrom by spacer bars 95

31, are ratchets 32 each adapted to coöperate with the tooth 33 on a bell-crank lever 34 fulcrumed at its forward end, as indicated at 35, to the carriage 11, it being understood that one of these levers 34 is provided at 100 each side of the carriage 11, these levers being so arranged that they normally hold the ratchets 32 against anti-clockwise rotation in Figs. 2 and 3, for the purpose hereinafter explained. The forward upwardly-projecting ends of the levers 34 are connected with a chain 36 which extends around a pulley 37 journaled on a pin 38 on the head 26 and connects, as indicated at 39, with a traveling block 40 provided with a pulley 41 110 by which this block is supported on, and is movable along the cable-way 5, this block

being provided for coöperation with a stop 42 which may be set at any point on the cable-way 5 and which controls the point at which the bucket dumps, as hereinafter described. The carriage 11 and bucket 18 are adapted to be operated through the medium of the hauling-line, the section of which beyond the block 26 is indicated at 43, this line passing over a pulley 44 on the mast 7 and connecting with a drum 45 operated in any suitable manner. The plates 12 and 13 are preferably held in properly spaced relation to each other by sleeves, forming spacers, on the bolts 17 and 28, as shown in Fig. 4, and on the bolts 14 in a similar manner.

In the operation of the apparatus, assuming it to be in scraping position (Fig. 1) wherein the cable 5 is slack and the bucket 18 lies on the material to be operated, the bucket is dragged along the material by pulling on the hauling-line which causes the bucket to fill. As soon as the bucket has filled, the operator, by operating the drum 10, draws the cable 5 taut, and by continued pull on the hauling-line hauls the bucket 18 and carriage 11 up the cable 5, the carriage, bucket and the parts connected therewith assuming the positions as represented in Fig. 2, in which positions, it will be noted, the bucket 18 is held in a position to prevent its contents from dumping, the pawl members 34, by reason of their heavier rear ends, engaging with the sprockets 32 which prevents the bucket 18 from prematurely swinging to dumping position should the hauling-line become slack during the operation of transferring the bucket from filling to dumping position. The stop 42 being in the path of movement of the block 40, as soon as this block, by continued pull on the hauling-line 1, moves into engagement with the stop 42, its farther movement upward along the cable-way 5 is prevented with the result, upon continuing draft on the hauling-line, of causing the carriage 11 to move upwardly on the cable at about twice the speed of the movement of the hauling-line. As soon as the block 40 strikes the stop 42, the levers 34 are rocked upwardly, thereby disengaging the teeth 33 from the ratchet wheels 32. The movement of the carriage 11 up the cable-way 5 relative to the hauling-line, upon engagement of the block 40 with the stop 42, as described, causes the branch-sections 24 and 25 of the hauling-line to become slackened, and as the sprocket 27 is free to rotate in anti-clockwise direction, by reason of the disengagement of the teeth 33 from the ratchets 32, as above stated, the bucket 18 is free to swing by gravity to dumping position, as represented in Fig. 3.

While I have illustrated and described a particular embodiment of my invention, I do not wish to be understood as intending

to limit it thereto, as the same may be variously modified and altered without departing from the spirit of my invention, it being my intention to claim my invention as broadly and completely as the prior state of the art will permit.

What I claim as new and desire to secure by Letters Patent is—

1. In apparatus of the character set forth, the combination of a main cable, a carriage movable thereon, a scraper-bucket pivotally mounted on said carriage in the rear of the center of gravity of the bucket when loaded, a hauling-line connected with said bucket in advance of its center of gravity for pulling the bucket along said main cable, means for releasably holding said bucket in load-carrying position, and means operated by continuous forward movement of said hauling-line for releasing said first-named means and for permitting said bucket to swing on its pivot to dumping position during said continuous movement of the hauling-line.

2. In apparatus of the character set forth, the combination of a main cable, a carriage movable thereon, a scraper-bucket pivotally mounted on said carriage in the rear of the center of gravity of the bucket when loaded, a hauling-line connected with said bucket in advance of its center of gravity, and engaging said carriage, for pulling said bucket along said main cable, means engaging the portion of said hauling-line which engages said carriage for releasably holding said bucket in load-carrying position, and means operated by continuous forward movement of said hauling line for releasing said first-named means and for permitting said bucket to swing on its pivot to dumping position during said continuous movement of the hauling-line.

3. In apparatus of the character set forth, the combination of a main cable, a carriage movable thereon, a scraper-bucket pivotally mounted on said carriage in the rear of the center of gravity of the bucket when loaded, a hauling-line connected with said bucket in advance of its center of gravity for pulling the bucket along said main cable, means for releasably holding said bucket in load-carrying position, and means engaging said hauling-line in advance of said bucket operating at a predetermined point to release said first-named means and to accelerate the movement of said carriage along said main cable relative to the movement of said hauling-line, for the purpose set forth.

4. In apparatus of the character set forth, the combination of a main cable, a carriage movable thereon, a scraper-bucket pivotally mounted on said carriage in the rear of the center of gravity of the bucket when loaded, a hauling-line connected with said bucket in advance of its center of gravity for pulling the bucket along said main cable, means on

said carriage for releasably holding said bucket in load-carrying position, a block running on said main cable, a stop on said cable in the path of movement of said block, 5 and a cable connecting said block and said first-named means and operatively engaging said hauling-line, for the purpose set forth.

5. In apparatus of the character set forth, the combination of a main cable, a carriage 10 movable thereon, a scraper-bucket pivotally mounted on said carriage in the rear of the center of gravity of the bucket when loaded, a hauling-line for pulling the bucket along said main cable, formed of sections connect- 15 ed with said bucket in advance of its center of gravity, one of said sections extending in engagement with said carriage, means for releasably holding said bucket in load-carrying position, and means connected with 20 said first-named means operating by continuous forward movement of said hauling-line for releasing said first-named means and for permitting said hauling-line sections to become slackened.

25 6. In apparatus of the character set forth, the combination of a main cable, a carriage movable thereon, a scraper-bucket pivotally mounted on said carriage in the rear of the center of gravity of the bucket when loaded, 30 a hauling-line for pulling the bucket along said main cable, formed of sections connected with said bucket in advance of its center of gravity, one of said sections extending in engagement with said carriage, means for 35 releasably holding said bucket in load-carrying position, a block running on said main cable, a stop on said cable in the path of movement of said block; and a cable connected with said block and with said first- 40 named means and operatively engaging said hauling-line, for the purpose set forth.

7. In apparatus of the character set forth, the combination of a main cable, a carriage 45 movable thereon, a scraper-bucket pivotally mounted on said carriage in the rear of the center of gravity of the bucket when loaded, a hauling-line for pulling the bucket along said main cable formed of sections connected with said bucket in advance of its center of

gravity, a sprocket on said carriage over 50 which one of said hauling-line sections ex- tends, pawl and ratchet means on said car- riage connected with said sprocket for re- 55 leasably holding the latter against rotation in one direction, and means operated by con- tinuous forward movement of said hauling- line for disengaging said pawl and ratchet means and for permitting said hauling-line sections to become slackened.

8. In apparatus of the character set forth, 60 the combination of a main cable, a carriage movable thereon, a scraper-bucket pivotally mounted on said carriage in the rear of the center of gravity of the bucket when loaded, a hauling-line for pulling the bucket along 65 said main cable formed of sections connect- ed with said bucket in advance of its cen- ter of gravity, a sprocket on said carriage over which one of said hauling-line sections extends, a ratchet connected with said 70 sprocket, a pawl-lever coöperating with said ratchet, and means operated by continuous forward movement of said hauling-line for moving said lever out of engagement with 75 said ratchet and for permitting said haul- ing-line sections to become slackened.

9. In apparatus of the character set forth, the combination of a main cable, a carriage 80 movable thereon, a scraper-bucket pivotally mounted on said carriage in the rear of the center of gravity of the bucket when loaded, a hauling-line for pulling the bucket along 85 said main cable formed of sections connected with said bucket in advance of its center of gravity, a sprocket on said carriage over which one of said hauling-line sections extends, a ratchet connected with said 90 sprocket, a pawl lever coöperating with said ratchet, a block running on said main cable, a stop on said main cable extending into the path of movement of said block, and a cable connected with said block and with said pawl-lever and operatively engaging said hauling-line, for the purpose set forth.

HENRY B. SAUERMAN.
